C. E. Way

By Clarence A. O'Brien
Attorney

UNITED STATES PATENT OFFICE

CHARLES E. WAY, OF FAIRMONT, OKLAHOMA

GATE LATCH

Application filed July 22, 1930. Serial No. 469,811.

This invention relates broadly to latches for retaining a closure normally in a closed locking position, the primary object of the invention being to provide a latch especially adapted for use with any gate, for retaining a gate closed.

A still further object of the invention is to provide a latch of the above-mentioned character which is comparatively simple in construction though reliable, practicable and efficient in use, and well adapted for the purpose for which it is designed.

Other objects and advantages of the invention will become apparent during a study 15 of the following description, taken in connection with the accompanying drawings, wherein:—

Figure 1 is a side elevational view of my improved latch.

20 Fig. 2 is a top plan view of the same taken on the line 2—2 of Fig. 1.

Fig. 3 is a sectional view of the latch taken on the line 3—3 of Fig. 1.

25 Fig. 4 is a plan view of the plate in conjunction with the catch plate, to be used in connection with the latch.

With reference more in detail to the drawings, it will be seen that the reference character G designates a gate. The gate as 30 shown comprises a metallic frame having vertical and horizontal bars or wires, connecting opposite members of the frame.

35 My improved latch comprises a substantially V-shaped member 5 formed of wire or any other suitable material. The V-shaped member 5 has the ends thereof passed through suitable openings provided in one vertical frame member of the gate and nuts 6 are threaded on said ends of the member 5 40 for retaining the same in position.

Intermediate its ends, the member 5 is looped about itself to provide an eye 7. A latch bar 8 at one end is provided with an eye 9 engaging eye 7 providing a loose connection between the member 5 and latch bar 8. The latch bar 8 has the free end thereof operable in a vertical slot 11 provided therefor in the said one vertical frame member of the gate G.

50 The free end of the bar 8 is adapted to be

moved into and out of engagement with an angular shaped notch 12 formed in the fence post P. As suggested, in this instance, the fence post P is of cylindrical formation and is preferably hollow. For normally retaining the free end of the bar 8 in the lower end of the vertical arm of the notch 12, there is arranged in the notch 11, a coiled spring 13 one end of which bears against the upper end of the notch, and the lower end of which bears against an intermediate portion of the bar 8.

It is thought that the operation of the device will be apparent from the foregoing description taken in connection with the accompanying drawings. When the parts are in the position shown in Fig. 1, and the gate is inclosed position, it may be normally maintained in that position by the free end of the bar 8 being held in engagement with the vertical section of the angular notch 12 through the medium of spring 13.

To swing the gate G to an open position, latch 8 is moved upwardly against the action of spring 13, and then moved laterally and downwardly to be finally withdrawn from the notch 12 as the gate is swung in the proper direction.

In Fig. 4, I have shown a plate designated generally by the reference character 14. This plate 14 is adapted to be used on a gate post which is made of wood. The plate 14 is provided with a notch 15 and the plate is further provided with an inwardly extending cutaway portion to provide an entrance opening 16 for the notch 15, the lateral opening 16 extending at an angle to the notch 15.

In use the plate 14 may be suitably secured to the wood gate post, and it will be seen that as the gate is swung to a closed position, the free end of the bar 8 will enter the opening 16 to move upwardly in a direction of inclination of the opening 16 to pass into notch 15 in finally dropping into the lower end of the notch for retaining the gate in closed position.

Even though I have herein shown and described the preferred embodiment of my invention, it is to be understood that changes may be made in the spirit of the invention,

and the scope of the appended claims without departing from the spirit of the invention.

Having thus described my invention, what I claim as new is:

1. A latch for the purpose specified comprising a substantially V-shaped member having the ends thereof capable of being passed through openings provided therefor in a closure, nuts threaded on the said ends for securing the member in position, said member at the apex thereof provided with an eye, a latch bar at one end provided with an eye engaging the first mentioned eye, the free end of said latch bar adapted to extend through a slot provided in the closure, and a spring in the slot normally urging the latch bar adjacent one end of the slot.
2. A latch for the purpose specified comprising a member formed of wire and coiled intermediate its ends to provide an eye, opposite end portions of the wire extending in divergent relation from said eye, a latch bar provided at one end with an eye engageable with the first mentioned eye, and means for securing the terminals of said opposite end portions to a support.

In testimony whereof I affix my signature.

CHARLES E. WAY.
